A. F. BARNES

CONCRETE PILING

Filed March 31, 1923

Albert F. Barnes Inventor
By his Attorney

Ivan E. A. Konigsberg

UNITED STATES PATENT OFFICE.

ALBERT FENTON BARNES, OF BROOKLYN, NEW YORK.

CONCRETE PILING.

Application filed March 31, 1923. Serial No. 629,004.

This invention relates to improvements in concrete piling and the object of the invention is to provide pre-cast concrete pile sections as new articles of manufacture, and 5 also to provide new methods for constructing concrete piles on the spot.

More particularly the invention contemplates the casting of sections of concrete piles at places remote from the place of application, though, of course, the invention is 10 not intended to be limited to this particular phase.

Speaking of pre-cast concrete pile sections, I refer to sections adapted to be used for the 15 purpose of building up a concrete pile on the place of application by driving one or more pre-cast sections into the ground and thereafter adding to the length of the pile by additional superimposed sections.

20 One object of the invention is to provide an improved concrete pile section consisting of an outer metal shell or casing filled with concrete. The casing serves as a form to retain the wet concrete until it is set, and also 25 serves as a reinforcement of the pile, the several jointed sections being united into an entire reinforced concrete pile, which, because of its construction, may be manufactured at one place, that is, pre-cast, and 30 shipped to another place where it is to be used.

With the above and other ancillary objects in view, my invention consists in a 35 pre-cast, or made on the spot, reinforced concrete pile section together with the means for joining the several sections, as well as in the method of practicing the invention. In the accompanying drawing:

Figure 1 is a sectional view of a concrete 40 pile manufactured as a unit and comprising several sections.

Figure 2 is a sectional view of a shorter section of pre-cast concrete piling adapted 45 to be united to the unit shown in Figure 1.

Figure 3 is an outside view of the jointed 50 pile sections, with parts in section and broken away.

Figure 4 is a cross sectional view of the 55 casing.

Figure 5 is a cross sectional view of another form of casing.

Figure 6 is a longitudinal section view 60 of a portion of a pile showing modified means for bonding the concrete and the casing.

Figure 7 illustrates in section a reinforced joint used in the piling.

Figure 8 shows in section a pile consisting partly of wood and partly of concrete 65 piling.

Figure 9 illustrates a method of driving a concrete pile into the ground utilizing certain features of the invention.

Referring to Figure 1 my improved concrete pile unit consists of an outer metal 70 casing filled with concrete. In this instance the casing consists of three sections designated 10, 11 and 12. The casing sections are cylindrical and may be tapered or straight.

The sections of the casing are formed into a cylinder as shown in Figure 4 and are thereafter joined together to form the entire casing for the unit. The joints may be of several forms. Thus at 13 I have shown 75 a joint made by means of an outer sleeve. The ends of the sections 10 and 11 may be welded together, or welded together with the sleeve. In this case the sections are of uniform diameter.

A tapered section 12 may be joined to the section 11 by a joint as shown at 14 where the lower end of the section is serrated or formed with teeth 14 so that when the concrete is poured in, the several teeth 80 may be firmly embedded in the concrete and thus strengthen the bond or union.

After the casing has been formed, the concrete 20 is poured in and at the same time a driving point 15 is formed at the 85 lower end of the unit, while a recess or unfilled space 16 is left at the top as a means for adding another section if the unit is not of sufficient length.

In the event it should be desired to reinforce the joints at 13 and 14, I may use any suitable reinforcement. As illustrated in Figure 7 vertical reinforcing means 17 or horizontal reinforcing means 18, or both 90 may be used as will be understood. The joint 21 shown in Figure 7 may be riveted or welded or both.

It will be seen, therefore, that as illustrated in Figure 1 this invention provides a pre-cast reinforced concrete pile unit 100 which may be handled, shipped, erected for driving and driven into the ground. It is obvious that this presents several advantages. Thus the unit may be made at any time and place and when most convenient. 110

It may be made in sizes and dimensions to suit and by several different methods and means. If the unit should happen to be of the right length for the job, the recess 16 at the top forms an excellent means for attaching other parts to the pile, such as flooring, beams or the like.

Figure 2 illustrates a unit which is made of a single section, or shorter section of casing 22 filled with concrete 20. This unit may also be pre-cast away from the job. The casing 22 is filled clear to the bottom as at 23 and at the top a recess 26 is formed corresponding to the recess 16 aforesaid. 15 In this case the unit 22 is tapered for convenient insertion or addition to the lower unit.

This is illustrated in Figure 3 in elevation and with parts broken away. The uppermost unit 22 is joined by first spreading mortar 24 in the recess 16, and thereafter inserting or adding the upper unit. The mortar unites and binds the two units together, and they are then driven into the ground. The pile may thus be lengthened as required by adding units at the top. And of course, a unit having several sections may also be thus added if found convenient.

In assembling the casings, the longitudinal joints 25 will preferably be staggered as shown in Figure 3 and these points or seams may be made in any suitable manner.

The casings may be corrugated or otherwise formed as shown in Figure 5 for better bonding with the concrete and better frictional driving into the ground. Or the casing may have projection or indentations 27 as shown in Figure 6 for the same purpose.

It is sometimes desirable to use a wooden pile for the lowermost unit. In that event a construction or method such as shown in Figure 8 may be employed. In this figure the upper part of the wooden pile 28 is shown. When it has been driven down, an iron or other suitable pipe 29 is placed on the wooden pile and with the upper edge also serrated or shaped with teeth 30 in the same manner and for the same purpose as described under Figure 1.

50 A casing section 31 is slipped down over the pipe 30 a suitable length, and thereafter concrete 20 will be poured into the casing 31. The concrete, as is obvious, forms a firm bond between the pipe and the casing, and when driving operation is resumed, the iron pipe is driven firmly into the wood pile.

Figure 9 illustrates a condition where a unit, such for instance as the unit shown in Figure 1, has been driven down to surface level, yet requires further driving, while on the other hand it is not desirable to lengthen

the pile by a section such as shown in Figure 2. In such case I may take an empty casing section 12, bend the teeth 14 inwardly, then place a wooden follower 35 within the casing 12 and drive on the follower.

It will be observed that the empty casing section 12 is well adapted for the purpose inasmuch as it fits within the pocket 16 in the uppermost preceding section and during the driving on the follower 35 the casing 12 serves as a means for aligning the two casings 12, 12. And when proper depth has been reached, and the follower withdrawn, the form and the reinforcement, that is, the empty casing 12 is in place and ready for pouring to the proper level, the inturned teeth 14 serving as a means for binding the two sections together.

It will be seen from the foregoing that the main principle of the invention, namely that of pre-casting sections or units of different length, and some of which may again consist of several sections, may be carried out by very simple yet efficient methods, and that it lends itself with great ease to the further developing of the concrete pile by additions of similarly made sections or units. Also that means are herein disclosed for bonding the joints and splicing, as it were, the several sections together and at the same time reinforcing the joints.

Again, that where special conditions require it, the precast units may be added to or driven or otherwise manipulated to suit.

I wish it of course understood that nothing herein contained is intended as a limitation but as an illustration and disclosure of the invention, and that details may be changed without departing from the spirit of the invention or the scope of the appended claims.

I claim:—

1. As a new article of manufacture a portable reinforced concrete pile unit consisting of a slightly tapered cylindrical metal casing filled with concrete, said casing serving as a form for the concrete for pouring and setting purposes and as a reinforcement in the manipulating and using of said concrete pile unit.

2. As a new article of manufacture, a portable reinforced concrete pile unit consisting of a plurality of sections of sheet metal cylindrical casings, means for joining said casings endwise to form a single unitary casing for the unit and concrete poured into said sheet metal casing to within a short distance from the upper end thereof whereby to form a recess for the reception of an additional unit.

ALBERT FENTON BARNES.
